COMBINED CONTACT LENS SUPPORT AND MIRROR FOR AN OPHTHALMOMETER

Newton K. Wesley, Chicago, and George S. Mattie, Palatine, Ill., assignors to Plasmatic, Inc., Des Plaines, Ill., a corporation of Illinois

Filed May 4, 1959, Ser. No. 55,770

Term of patent 14 years

(Cl. D57—1)

Fig. 1 is a perspective view of a combined contact lens support and mirror for an ophthalmometer, showing our new design;

Fig. 2 is a side elevational view thereof;

Fig. 3 is a rear elevational view thereof;

Fig. 4 is a side elevational view thereof from the reverse side with respect to Fig. 2; and

Fig. 5 is a plan view thereof.

We claim:

The ornamental design for a combined contact lens support and mirror for an ophthalmometer, substantially as shown.
